UNITED STATES PATENT OFFICE.

PETER FURST, OF ANDERSON, INDIANA.

GAS AND GASOLENE ENGINE.

No. 857,455.

Specification of Letters Patent.

Patented June 18, 1907.

Application filed November 29, 1904. Serial No. 234,763.

To all whom it may concern:

Be it known that I, PETER FURST, a citizen of the United States, residing at Anderson, in the county of Madison and State of Indiana, have invented new and useful Improvements in Gas and Gasolene Engines, of which the following is a specification.

This invention relates to explosive engines of the type in which gas or gasoline is employed as the driving medium and embodies in its organization a supporting frame having a pair of opposed cylinders pivoted for oscillation therein and provided with surrounding jackets receiving a cooling medium, there being arranged for reciprocation in the cylinders a pair of pistons connected with the drive shaft, in turn journaled in the frame at a point between the cylinders, which are provided with valve controlled inlet and exhaust ports.

The invention has for its objects to provide a comparatively simple, inexpensive device of this character wherein a direct connection may be had between the pistons and drive shaft and this owing to the oscillatory movement of the cylinders, one wherein the cooling medium may be introduced into and discharged from the jackets through the journals of the cylinders, and one wherein the inlet and exhaust ducts for conveying the motive fluid are journaled concentrically with the pivotal axes of the cylinders, thereby permitting free oscillation of the latter.

A further object of the invention is to provide an improved mechanism for automatically and alternately operating the exhaust valves of the respective cylinders at proper predetermined intervals.

To these ends the invention comprises the novel features of construction and combination of parts more fully hereinafter described.

In the accompanying drawings, Figure 1 is a side elevation of an engine embodying the invention. Fig. 2 is a vertical longitudinal section taken centrally through the same. Fig. 3 is a central horizontal sectional plan, the section being taken on the line 3—3 of Fig. 2.

Referring to the drawings, 1 designates a supporting frame having journaled at its longitudinal center for rotation a power shaft 2 provided with oppositely disposed crank portions 3, there being fixed upon the shaft a balance wheel 4, a belt pulley 5 and a toothed pinion 6.

Pivoted in the frame for oscillation is a

pair of cylinders 7 arranged respectively at opposite sides of the shaft 2, these cylinders being surrounded by water jackets 8 carrying integral tubular journals 9 constituting the pivotal axes of the cylinders and having bearing in suitable boxes 10 carried by the frame. The boxes 10 are adapted for adjustment in a direction longitudinally of the frame by means of adjusting members or screws 11 and in a direction transversely of the frame through the medium of auxiliary adjusting members 12 for a purpose which will hereinafter appear.

Arranged for reciprocation as usual in the cylinders 7 are pistons 13 of ordinary construction carried by piston rods 14 coupled respectively directly with the crank portions 3 of the shaft, while each cylinder 7 has communicating with its jacket 8, through the medium of the hollow journals 9, an inlet pipe or duct 15 coupled to one of the journals and a discharge pipe or duct 16 coupled to the other journal, whereby water or other suitable cooling medium may be readily admitted to and for circulation through the duct around the cylinder and be finally discharged from the jacket.

Coupled to each cylinder at the outer or rear end of the latter is an inlet pipe or duct 17 and an oppositely disposed exhaust pipe or duct 18 adapted respectively for admitting the charges of gas, gasoline or other motive fluid and exhausting the gases and other products of combustion after the explosion of the charges, these pipes, which are angularly bent as illustrated in Fig. 3, being pivoted or journaled in boxes or bearings 19 arranged concentric with the journals 9 and connected to the cylinders by means of swivel joints or couplings 20 whereby free movement or oscillation of the cylinders upon their axes is permitted.

Arranged in the intake pipes 17 are normally closed puppet valves 21 adapted to open automatically under the influence of the suction or vacuum created by the cutward strokes of the pistons to thus permit a charge of gas to enter the cylinders, while the exhaust pipes 18 are provided with vertically disposed normally closed exhaust valves 22 provided with stems 23 which normally rest at their outer or lower ends upon operating members or levers 24, each pivoted at one end to its cylinder and provided at its other or free end with a cam portion or head 25, there being arranged in the stuffing

boxes through which the valve stems 23 work normally expanded springs 26 for maintaining the valves in closed position.

Suitably journaled in the frame 1 immediately beneath the shaft 2 is a stub shaft 27 on which is fixed a double headed cam member 28 and a gear 29 in mesh with the pinion 6, the heads 29 of the cam member being adapted to act alternately and respectively upon auxiliary operating members or levers 30 pivoted between their ends to the frame 1 and acting in turn at their outer ends upon the cam heads 25 of the main members 24 for opening the valves 22.

In practice, and under the impulse of a charge of gas exploded in one, say, for example, the left-hand cylinder, the pistons, which work in unison, will be driven outwardly, thereby drawing a charge into the right-hand cylinder, whereby on the instroke of the pistons the gases and other products of explosion will be exhausted from the left-hand cylinder and the charge of fluid in the other cylinder be compressed. The compressed charge in the right-hand cylinder is then exploded for carrying the piston on the outstroke, thus drawing a second charge into the left-hand cylinder for compression upon the instroke of its piston, this action being continued throughout the period of operation of the engine. During the movements of the pistons their respective cylinders will be oscillated upon their pivots, thus insuring at all times a direct movement of the pistons and at the same time minimizing friction on the parts and the wear incident to such friction, this oscillation of the cylinders being rendered feasible owing to the inlet and exhaust pipes being journaled concentric with the pivotal axes of the cylinders. On the instroke of the pistons for effecting exhaust the cam heads 29 will act upon the adjacent ends of the levers 30 and, through the medium of the levers 24, open the exhaust

valves, it being understood, of course, that the position of the cams upon the shaft and the timing of the movement of the parts is such that the exhaust valves will be opened in the respective cylinders alternately and at proper intervals. It may be mentioned that owing to the journals 9 being pivoted in boxes which have an adjustment longitudinally of the frame and through the adjustment of the journals in a direction transversely of the frame the cylinders may be readily positioned relative to the shaft when initially setting up the engine and to compensate for wear during the operation of the latter.

Having thus fully described the invention, what is claimed as new, is:

In an engine, a frame, a pair of opposed cylinders pivoted for oscillation therein, said cylinders being provided with inlet and exhaust ports, a drive shaft journaled in the frame between the cylinders and having crank portions, pistons arranged for reciprocation in the cylinders and having their rods connected directly with the respective crank portions of the shaft, spring pressed valves arranged for normally closing the exhaust ports, operating members pivotally mounted on the cylinders in position to act upon the exhaust valves, pivoted auxiliary levers disposed to act respectively on said members for opening the valves, a stub shaft journaled in the frame beneath the drive shaft, gear connections between the shafts for rotating the stub shaft and a double cam member fixed on the latter and adapted to positively actuate the auxiliary levers.

In testimony whereof, I affix my signature in presence of two witnesses.

PETER FURST.
